UNITED STATES PATENT OFFICE.

GEORGE W. ALLEN, OF HYDE PARK, MASSACHUSETTS, ASSIGNOR TO B. F. STURTEVANT COMPANY, OF BOSTON, MASSACHUSETTS, A CORPORATION OF MASSACHUSETTS.

JOURNAL-BEARING.

1,115,369.

Specification of Letters Patent. Patented Oct. 27, 1914.

Application filed December 26, 1907. Serial No. 408,173.

To all whom it may concern:

Be it known that I, GEORGE W. ALLEN, citizen of the United States, residing at Hyde Park, in the county of Norfolk and 5 State of Massachusetts, have invented certain new and useful Improvements in Journal-Bearings; and I do hereby declare the following to be a full, clear, and exact description of the invention, such as will enable others skilled in the art to which it 10 pertains to make and use the same.

The present invention relates to journal bearings, and the object of the present invention is to provide an adjustable journal 15 bearing which shall be of simple and cheap construction, and which shall be firm and solid in all positions within the range of adjustment.

With these objects in view, the present invention consists of the devices and combinations of devices hereinafter described and claimed.

In the accompanying sheet of drawings which illustrate the preferred form of the 25 present invention, Figure 1 is an end elevation of the assembled bearing; Fig. 2 is a perspective of the pillow block; Fig. 3 is a top plan of the journal housing and the adjusting wedges; and Fig. 4 is a vertical section on line 4—4, Fig. 3.

As shown in the drawings, the housing 1 for the bearing comprises a base and sides rising vertically therefrom. Fitted within this housing and loosely enough to provide 35 for proper adjustment is the pillow block 2, in which is formed or carried the lower half of the bearing proper. The pillow block is provided with substantially vertical ends 3, sides 4, and flat bottom 5. The four bottom 40 corners are beveled, as it were, giving inclined plane surfaces 6. A smaller beveled surface 7 connects each side 4 with the bottom 5. The beveled corners of the pillow block are engaged by two pairs of wedges 8 having inclined surfaces, and the two 45 wedges of each pair are moved toward and from each other by means of a right and left-hand threaded spindle 9, having a squared end 10 to receive a wrench by which 50 the spindle may be turned. The upper part of the bearing is formed in or carried by a cap 11 having the downwardly projecting tongues 12 which enter the rabbets 13 on the pillow block, the sides of the tongues engag-

ing the sides of the rabbets and holding the 55 cap in fixed position relative to the pillow block, so that the two halves of the bearing shall always remain in proper alinement. The cap is provided with four holes or slots through which pass studs 14, the dimension 60 of the slots parallel with the axis of the bearing being but slightly greater than the diameter of the studs, while the length of the slots at right angles to the axis of the bearing is considerably greater than the diameter 65 of the studs, so that the cap may be adjusted transverse to the axis of the bearing. Nuts 15 on the upper ends of the studs 14 secure the cap to the housing and hold the pillow block and adjusting wedges securely within 70 the housing. Shims 16 may be inserted between the cap and the pillow block, one or more of which may be removed from time to time to take up wear in the bearing.

The bearing is adjusted by actuating the 75 threaded spindles 9. For instance, if the nuts 15 be slightly loosened and the left-hand spindle 10, shown in Figs. 1 and 3, be turned clock-wise, the wedges 8 will be drawn toward each other, forcing the pillow 80 block and cap to the right and upward. If the right-hand spindle be turned in the same direction at the same time, the pillow block and cap will be forced in a vertical direction, while if one spindle be turned in one 85 direction and the other spindle in the other direction and to the same extent, the block and cap will be moved horizontally in one direction or the other. The bearing may be thus adjusted in any direction and to any 90 extent within the limits.

Not only is the present form of bearing simple in its arrangement and exceedingly cheap in construction, owing to the fact that very little machining is necessary, and owing 95 to the self adjustability of the parts, which avoids the necessity of extreme accuracy in their shape and dimensions, but the pillow block being supported upon plane surfaces is firmly held at all times, no matter what its adjustment may be.

Having set forth the nature and object of the invention, and specifically described one form of apparatus in which it may be embodied, what is claimed is:—

1. A journal bearing comprising a housing, a pillow block fitting loosely within the housing, and having four plane surfaces an-

gularly disposed each to the other, wedges coöperating with said surfaces on the pillow block, and means for moving the wedges to adjust the pillow block, substantially as described.

2. A journal bearing comprising a housing having a base, a pillow block fitting loosely within the housing and adapted to be adjusted transversely of the axis of said bearing in both a vertical and a horizontal direction, and having a plurality of plane surfaces inclined to each other and to both the vertical and horizontal transverse axes of said bearing, and wedges between the pillow block and the base of the housing to adjust the pillow block in the housing, substantially as described.

3. A journal bearing comprising a housing having a base and sides at right angles to said base, a pillow block fitting loosely within the housing and adapted to be adjusted toward and from said base and toward and from said sides, and having a plurality of plane surfaces inclined to each other and to both the base and the sides of the housing, movable wedges engaging the base and sides of the housing and coöperating with said inclined surfaces for adjusting the pillow block, a cap, and means for clamping the cap to the housing to hold the pillow block in adjusted position in the housing, substantially as described.

4. A journal bearing comprising a housing, a pillow block fitting loosely within the housing and having its four bottom corners beveled, wedges for engaging the beveled corners, and means for moving the wedges to adjust the pillow block, substantially as described.

40 5. A journal bearing comprising a rectangular housing, a pillow block fitting loosely within the housing and having its bottom corners beveled, wedges for engaging the beveled corners of the pillow block, means for moving each of a pair of wedges simultaneously toward or from each other, a cap held in fixed position relative to the pillow block, and means for securing the cap to the housing having provision for vertical and transverse adjustment of the cap, substantially as described.

55 6. A journal bearing comprising a housing, a pillow block fitting loosely within the housing and provided with a plurality of inclined plane surfaces, a plurality of wedges movable in the same plane in parallel paths and having inclined plane faces intersecting the plane of movement of the wedges in lines

oblique to the path of movement of said wedges, substantially as described.

7. A journal bearing comprising a pillow block provided with a plurality of plane faces inclined to each other and to the vertical and horizontal transverse axes of the bearing, a plurality of wedges having inclined plane surfaces for supporting the pillow block and movable to adjust the pillow block transversely of the axis both vertically and horizontally, a support for the wedges, and means having provision for adjustment of the pillow block both horizontally and vertically transverse of the axis of the bearing for clamping the pillow block upon the wedges in adjusted position, substantially as described.

8. A journal bearing comprising a housing, a pillow block fitting loosely within the housing, having its four bottom corners beveled, and having a shoulder at its top, wedges for engaging the beveled corners of the pillow block, the wedges being connected in pairs by spindles having right and left-hand threads, a cap having a shoulder for engagement with the shoulder on the pillow block to prevent relative movement of the pillow block and cap transverse to the axis of the bearing, and means having provision for vertical and transverse adjustment of the cap and block for securing the cap to the housing and for holding the cap and block in the adjusted position, substantially as described.

9. A journal bearing comprising a housing, a pillow block adjustable within the housing and having four plane surfaces angularly disposed each to the other and to the axis of the bearing, movable wedges coöperating with said plane surfaces to adjust the pillow block, and means for securing the pillow block in adjusted position, substantially as described.

10. A journal bearing comprising a pillow block having diagonally opposite bottom corners beveled, wedges for engaging the beveled corners to support the pillow block, means for moving the wedges to adjust the pillow block, and devices for securing the pillow block in adjusted position, substantially as described.

In testimony whereof I affix my signature, in presence of two witnesses.

GEORGE W. ALLEN.
